UNITED STATES PATENT OFFICE.

EMIL G. JEGGE, OF NEWARK, NEW JERSEY.

PRESS.

1,030,408.

Specification of Letters Patent. Patented June 25, 1912.

Application filed September 22, 1911. Serial No. 650,691.

To all whom it may concern:

Be it known that I, EMIL G. JEGGE, a citizen of the United States, residing at Newark, in the county of Essex and State of New Jersey, have invented certain new and useful Improvements in Presses; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a press which is provided with dies between which material is to be stamped or molded, and which dies are adapted to receive heating and cooling mediums to alternately heat and chill the dies, the press having mechanism for alternately permitting the admission of the mediums to the dies.

The invention further provides a press of this kind with means for regulating the speed of the press to regulate the time the dies are together, in other words, to submit the material to the action of the dies a predetermined space of time and to control the regulating means by a thermostatic device, which thermostatic device in turn is influenced by the heating and cooling mediums which are used in the dies.

In some materials when they are used in presses it is necessary to stamp them in warm or heated condition, or to have the dies heated, and after they are pressed in their warm condition to the required shape, the material requires cooling to either set the material in its molded shape and to make it hard, or to give it a polished finish. This is particularly true of a great many plastic materials, and to automatically regulate the heating and cooling of the material and to insure the contact of the dies with the material for the required space of time, this press has been devised.

The invention is somewhat diagrammatically illustrated in the accompanying drawing, in which—

Figure 1 is a view of a press of very simple form with the thermostatic means for controlling the operation of the press. Fig. 2 is a view of a modified form of means for regulating the starting and stopping or the speed of the press, and Fig. 3 is a view of

still another modified form of regulating means.

In the drawing I have illustrated a press of the type employing toggle-levers to force the movable die, but of course it will be understood that any form of press can be employed in my invention.

The press illustrated consists of the toggle-levers 11 which operate at one end on a suitable support 12, and on the other end on the movable die 13 which co-operates with the die 14 to press material between them. The toggle-joint is made and broken by means of an arm 15 operated by a cam 16 which engages the roller or pin 17 on the arm 15. The cam 16 rotates with the shaft 18 which is operated by the teeth 19 which in turn are driven by the worm 20. The worm is mounted on a driving-shaft 21 and is provided with a pulley 22 operated by a belt 23. It will be understood that the elements herein enumerated can be supplanted by their equivalents.

The dies 13 and 14 are adapted to receive and conduct heating mediums in the shape of fluids, and I prefer to use steam and water for the respective heating and cooling of the dies. The dies 13 and 14 are fed by pipes 24 and 25, respectively, which are connected to the valve 26, the valve also having the inlet pipes 27 and 28, one of which is used to conduct the heating medium and the other being used to conduct the cooling medium to the valve. The particular form of valve is not essential, but I prefer to employ a type of valve shown in my Patent No. 986,174 of March 7, 1911, and I also prefer to employ the general type of press shown in this patent.

The valve 26 alternately admits the heating and cooling mediums to both pipes 24 and 25 and is preferably operated from the die-operating mechanism. To accomplish this I illustrate the pulley 29 of the shaft 18 which has a belt 30 which in turn passes over the pulley 31 of the shaft 32. An eccentric 33 rocks the arm 34 which has a segmental gear thereon in mesh with the pinion 35 of the valve. The thermostatic mechanism 36 is connected by the pipes 37 and 38 with the dies so that the heating and cooling mediums are conducted to the expandible element 39 of the thermostatic mechanism, the expandible element being fixed at one end in a support 40 and having its movable

end 41 so disposed that it can be used to regulate the speed of the press in a manner to be hereinafter described. I prefer to make the expansible element hollow to receive the heating and cooling mediums and to be provided with an outlet 42 connected with an outlet pipe 43 which in turn is connected with the waste-pipe 44. The expansible element 39 is connected with a lever 45 pivoted at 46 and having its free end operatively connected with a rod 47. In Fig. 1 the rod 47 forms the stem of a valve 48 so that when the valve is open, fluid under pressure, such as air, can pass from the inlet 49 of the pipe 50 to the air-operated clutch 51 mounted on the main-shaft 21 and adapted to be thrown into and out of operative connection with the driving pulley 22.

The operation of the press is as follows:—
 20 Assuming that the press is in motion and starting from the position shown in Fig. 1, the arm 15 will be operated by the cam 16 to aline the toggle-levers 11 and force the die 13 in contact with the die 14, and at the 25 same time the valve 26 is operated to admit the hot medium to the valves 13 and 14 so that they are heated when they come together, and the material which is usually fed to the press heated, or if it is not, is heated 30 by contact with the dies, is molded into the required shape or configuration. The heating medium passes through the dies and through the pipes 37 and 38 to the thermostatic device 36 and heats the expansible element 39 so that it becomes longer and pushes the short end of the lever 45 against the spring 52 which abuts on the nut 53 on the rod 47 and closes the valve 48 as shown in Fig. 1. This releases the clutch 51 and the 40 press stops, since the clutch 51 is not under pressure. In the meantime, however, while this heating medium has been traveling through the pipes 37 and 38 to the thermostatic device, the valve has been turned to 45 admit the cooling medium which now follows the heating medium and drives the heating medium before it through the dies, chills the dies through the pipes 37 and 38 to the thermostatic device, shortens the expansible element, swings the lever 45 against the adjusting screw 54 on the rod 47, opens the valve 48, the clutch 51 is under pressure and is thrown into contact with the driving pulley 22 and the press again begins to operate and the dies are drawn apart. When the dies are apart, opportunity is presented for removing the stamped material, putting fresh material between the dies, the valve 26 has rotated far enough to 55 again admit heating medium to the pipes and the dies, and the sequence of the operation of the different elements is repeated as above described.

It will thus be seen that an automatically operated press is produced which stops and

starts automatically at predetermined times, requires no manual manipulation, and insures the heating and cooling of the material that is pressed. The spring 52 is installed to take up any excess expansion of the expansible element 39 and permit the lever 45 to swing after the valve 48 is shut. I install pipes 55 and 56 connecting the pipes 38 and 37, respectively, to the waste-pipe 44 when it is desired to use the press as a continuously operating press, and not have to stop or start automatically.

In Fig. 2 I show a modification of the clutch by replacing the hydraulic or pneumatic operating clutch 51 by a mechanical clutch 57 which is swung by the arm 58 which is reciprocated by the rod 47 which in turn is moved by the lever 45. This illustrates a strictly mechanical operation of the clutch without the employment of the pneumatic means shown in Fig. 1.

In Fig. 3 the main-shaft 21 is provided with a gear 59 in mesh with a gear 60 operated by an electric motor 61 which is in circuit with the wires 62 and 63 which are led from any suitable source of power. One terminal 64 of a switch is fixed, and the other terminal 65 is mounted on the rod 47 which is swung as before, by the lever 45. This form illustrates one means of electrically stopping and starting the press, in lieu of the pneumatic means shown in Fig. 1, and the mechanical means shown in Fig. 2.

Having thus described my invention, what I claim is:—

1. A press having dies adapted to receive heating and cooling mediums, mechanism for alternately feeding said mediums, and thermostatically operated means actuated by said mediums for regulating the operation of the dies.

2. A press having dies adapted to receive heating and cooling mediums, mechanism for alternately feeding said mediums to the dies, means for operating the dies, and thermostatically operated means actuated by said mediums for regulating the die-operating means.

3. A press having dies adapted to receive heating and cooling mediums, means for operating the dies, mechanism for alternately feeding the mediums to the dies, said mechanism being operated from the die-operating means, and thermostatically operated means actuated by said mediums for regulating the die-operating means.

4. A press having dies adapted to receive heating and cooling mediums, means for operating the dies toward and from each other, mechanism for alternately feeding the heating mediums to the dies, thermostatic means actuated by said mediums for regulating the die-operating means, and means for conducting the mediums from the dies to the thermostatic means.

5. A press having dies and operating means therefor, the dies being adapted to receive cooling and heating mediums, means for alternately feeding said mediums to the dies, an operative connection between the feeding means and the die-operating means, means for starting and stopping the die-operating means, and a thermostatic means operated by the mediums for actuating the starting and stopping means.
6. A press having dies and operating means therefor, the dies being adapted to receive heating and cooling mediums, means for alternately feeding the mediums to the dies, and thermostatic means adapted to receive the mediums from the dies and acting to start and stop the die-operating means.
7. A press having dies, means for operating the dies, the dies being adapted to receive and transmit heating and cooling mediums, a valve for alternately admitting the mediums to the dies, a thermostatic device for regulating the die-operating means,

and means for conducting the mediums from the dies to the thermostatic device.

8. A press having dies, means for operating the dies, the dies being adapted to receive and transmit heating and cooling mediums, a valve for alternately admitting the mediums, means for operating the valve from the die-operating means, means for regulating the stopping and starting of the die-operating means, a thermostatic device adapted to be actuated by the mediums and adapted to control the starting and stopping means of the die-operating means, and means for conducting the mediums from the dies to the thermostatic means.

In testimony, that I claim the foregoing, I have hereunto set my hand this 19th day of September, 1911.

EMIL G. JEGGE.
